Primary Examiner—Robert M. Spear

(74) Attorney, Agent, or Firm—Kilpatrick Stockton LLP; John S. Pratt, Esq.; Kyle M. Globerman, Esq.

(57) **CLAIM**

The ornamental design for a handle, as shown and described.

DESCRIPTION

FIG. 1 is a perspective view of my new design of the handle shown in a folded condition.

FIG. 2 is the front view of the handle of FIG. 1 shown in an open condition, the rear view being the same.

FIG. 3 is the right side view of the handle of FIG. 2, the left side view being the same.

FIG. 4 is the top view of the handle of FIG. 2, the bottom view being the same.

FIG. 5 is a perspective view of my new design of the handle shown in a folded condition in an alternate embodiment.

FIG. 6 is the front view of the handle of FIG. 5 shown in an open condition, the rear view being the same.

FIG. 7 is the right side view of the handle of FIG. 6, the left side view being the same; and,

FIG. 8 is the top view of the handle of FIG. 6, the bottom view being the same.
